UNITED STATES PATENT OFFICE

2,456,135

SHOE SUPPORT

Kenneth W. Macdonald, Winchester, Mass., assignor to Compo Shoe Machinery Corporation, Boston, Mass., a corporation of Delaware

Application April 29, 1943, Serial No. 485,007

7 Claims. (Cl. 12—126)

1

This invention relates to means for supporting shoes, whether carried on lasts or forms, for presentation to mechanism for operating on the shoes. While not restricted to supporting the shoe for any particular operation, the support for the present invention has been designed more particularly to suit the requirements of mechanism for pressing the contour portions of shoes into smooth contours with the adjacent surfaces of the shoe heels, and more particularly when the heels are of the wood heel type, where the heel seat margins of the heel are seated directly against the shoe upper. Such a mechanism is disclosed, for example, in my Patent No. 2,357,596 for Heel seat conforming machine, granted September 5, 1944. For such service it is necessary to adjust the height of the shoe, and the level of the heel seat portion, both longitudinally and laterally. This is complicated by varying positions and angularities of last pin holes in lasts or forms which may be off center or inclined from proper positions, or both, different heights of lasts or forms, and irregularities of positioning of shoes on lasts or forms.

It is also highly desirable to provide for supporting both right and left shoes on the same support, and for this purpose lateral adjustment of the jack pin and its holder as a unit is provided.

As applied to mechanisms for pressing the counter portion of a shoe in accordance with my patent hereinbefore noted, the pressing apparatus serves to automatically position the shoe properly laterally, both bodily and angularly, when proper adjustment for height and longitudinal angularity has been effected by the operator.

For a more complete understanding of this invention, reference may be had to the accompanying drawings, in which

Figure 1 is a fragmentary vertical sectional view of the support on line 1—1 of Figure 2.

Figure 2 is a similar sectional view on line 2—2 of Figure 1.

Figure 3 is an exploded perspective view of certain of the parts shown in Figures 1 and 2.

Figure 4 is a fragmentary top plan view to a smaller scale of a counter pressing mechanism employing the shoe support of this invention.

Figure 5 is a more complete top plan view of the machine than is Figure 4.

Figure 6 is a sectional view of the machine on line 6—6 of Figure 5.

Referring to the drawings, at 1 is indicated a base which carries the shoe supporting mech-

2

anism. It is provided with an upright socket 2 within which is slidably mounted a post 3. This post, as shown, is provided with a threaded bore 4 extending upwardly therein into which is engaged the upper threaded portion 5 of a shaft 6 journaled in the lower reduced diameter portion of the socket 2 and provided with a flange 7 seated on an annular shoulder 8 therein, which holds the shaft in proper position.

10 Below the base 1 the shaft 6 has keyed thereto a worm wheel 10 with which meshes a worm 11 carried by a horizontal shaft 12 journaled in the base and provided at its forward end convenient to the operator with a hand wheel 15 by which it may be turned, thus to adjust the post 3 vertically. At the upper end of this post, it is provided with an extension 20 projecting toward the operator and toward the toe portion of a shoe indicated by broken lines at 21 and carried by the support. This extension 20 is provided with an upright threaded hole 22 in which is engaged the upper threaded end portion of an abutment 23. The lower portion of this abutment is formed as a rod 24 which extends downwardly through a passage 25 in the base and has fixed to its lower end beneath this base, means such as a knurled knob 26, by which the rod 24 may be turned, thus raising or lowering the abutment 23. On this abutment rests 20 one end portion of a block 30 provided with a wall portion 31 resting upon the upper rounded end of the abutment 23. This block 30 is provided with an opening 32 therethrough into which the upper end of the post 3 extends, this opening 32 being considerably wider than the upper end of the post 3, as shown best in Figure 1. Through this upper end portion of the post and the side walls 33 of the block extends a pivot pin 34, the ends of which form a tight fit in the walls 33 and the intermediate portion of which is rockably mounted in a transverse hole 35 in the top of the post. This arrangement permits the angular position of the block to be adjusted about the axis of the pivot pin 34 by adjustment of the abutment 23, and it also permits free lateral sliding of the block lengthwise of the pin 34. This free or unconstrained rectilinear sliding motion is laterally of a shoe carried by the support, as shown in Figure 1 and permits free lateral adjustment of the shoe to provide for right and left shoes and for shoes supported on lasts or forms having varied positions of last pin holes and also for shoes that may be mounted in various positions on either lasts or forms. Quite often after lasting or sec-

ond lasting shoes, the last may be in the shoe either crooked or a little to one side or the other.

A jack pin 40 which may enter the last pin hole 41 of a last, or of a supporting form for the shoe in lieu of a last, is secured, as by threading into a yoke element 42, the ends of which overlap the ends of the block 30 and are pivoted thereto as on the pivot screws 45 which extend through downwardly extending ears 46 of the yoke member, the screws 45 being threaded into the ends of the block 30. Where a form is employed it is shaped like at least the rear portion of a last.

This pivotal motion of the yoke member 42 permits a free limited rocking motion of the pin 40 laterally of the shoe, this allowing for adjustment of the level of the heel seat of the shoe to permit the heel seat on each side to be brought into proper relation to a pair of side gages 50 inwardly extended from the upper face of the base 1. The level of the heel seat lengthwise of the shoe is adjustable by adjustment of the abutment 23, the last pin locating the shoe sufficiently near to the axis of the pivot 34 so that the shoe tends to tilt forwardly with the block 30 resting upon the abutments 23, while the shoe as a whole may be adjusted up and down by turning the handle 45. Thus the heel seat of a shoe whether right or left, and the heel seats of shoes mounted on forms or lasts with different positions of last pin holes or the heel seats of shoes which may be mounted in different positions on either lasts or forms may be brought into proper relation to the means which operates on the shoes, in an easy and expeditious manner.

In Figures 1 and 4 the shoe support is shown as associated with side and rear counter pressing form blocks 55 which are connected together to form a substantially continuous shoe-engaging face having a continuous surfacing layer 550 by arcuate keys 56 slidably related thereto. These blocks are arranged to be closed in about the heel end of a shoe supported on the last or form, and which is pushed rearwardly to the dotted line position into engagement therewith, by forward motion of the arms 57, having equalizer levers 58 engaging the forward pairs of blocks 55. This inward motion of the blocks 55, which in definite paths, acts by pressing engagement with one or the other side of the shoe automatically to correctly position the shoe laterally lengthwise of the pivot 34 and angularly about the axis of the pivots 45, so that the side edges of the heel seat come at the proper levels for the desired pressing operation when the height and the lengthwise angular adjustment have been properly made.

As shown also in my Patent No. 2,357,596, to which reference has already been made, the central block 55 has a pair of spaced upper and lower projections 60 (Figure 6) through which passes a pivot pin 61, the lower end of the pivot pin extending into a guide channel 62 in the top face of a table 63. This central block 55 is normally pressed forwardly toward the shoe support by means of a spring 64, the rear end of which is seated in a block 65 secured to the table 63. This permits the block 55 to be pressed rearwardly by engagement thereagainst of the heel end of a shoe 21 carried by the shoe support. Such rearward motion of the central block 55 acts to rock a pair of arms 66 pivoted one above the other on the pivot pin 61 engaging fixed stops 67 and bearing against the block 55

next adjacent to the central block 55. This tends to close these adjacent blocks against the shoe upper. The fixed stops 67 also constitute pivots for the arms 57 between rollers journaled at the

5 rear ends of which is positioned a wedge block 68 against which the rollers of the arms 57 are held by a spring 69. A thrust rod 70 extends from the rear larger end of the wedge block 68 and this rod 70 extends through a slide block 71.

10 A collar and nut on the rear end of the rod 70 limits the rearward motion of the slide block 71. A coil spring 72 surrounds the rod 70 and reacts between the slide block 71 and an adjustable collar 73 on the rod. The forward motion of the slide block 71 thus applies yielding forward pressure on the wedge block 68 and closing pressure of the wedge blocks 55 against the side portions of a shoe on the support adjacent to the shoe heel seat. As the shoe is free for lateral adjustment, this closing of the wedge blocks causes the shoe heel portion to be presented in the same lateral position whether it be of a right or left shoe.

Means are provided for moving the shoe support forwardly into inoperative or loading position and rearwardly into operative position with the heel portion of the shoe thereon in operative relation to the pressure mechanism, and for opening and closing the pressure mechanism in

20 suitably timed relation. This means may comprise a motor 75 geared to a drive shaft 76 carrying an eccentric 77, connected through a strap 78 and a link 79 to a bell crank lever 80 secured to a rock shaft 81. The slide block 71 is connected through a pair of links 82 to a pair of

30 rock arms 83 fixed to the rock shaft 81. Rotation of the shaft 76 is thus caused to open and close the pressure mechanism against the shoe. It is also connected to move the shoe support

40 forwardly and backwardly in proper timed relation to the opening and closing motions of the pressing mechanism. For this purpose, one arm 85 of the bell crank lever 80 has a pivot member 86 perforated for the slidable passage

45 of a link 87, connected at its forward end to the shoe support 1 which is slidably mounted in ways of the machine. The pivot member 86 engages a spring abutment 88 between which and nuts 89 on the rear end of the link 87 a coil spring 90 is positioned. A switch 91 controlled by a cam 92 on the shaft 76 limits the rotation of the shaft 76 at each actuation to one-half a revolution and cooperates with a treadle actuated starting switch 93 in the manner fully set forth in my Patent No. 2,357,596 so that the shoe support is alternately moved rearwardly into the pressing mechanism and the pressing mechanism is pressed against a shoe carried thereby, or the pressing mechanism is opened and the pressed shoe is moved forwardly for removal and replacement by a shoe to be pressed, at each actuation of the machine.

From the foregoing description of an embodiment of this invention, it should be evident to those skilled in the art that various changes and modifications might be made without departing from the spirit or scope of this invention.

I claim:

1. A device of the class described, comprising a supporting member, a block pivoted to said member on a substantially horizontal pivot and with freedom of motion between limits axially of said pivot, means for adjusting said block angularly about its pivot, a yoke pivotally supported on said block about an axis transverse to the direction of

said block pivot for limited pivotal motion, and a jack pin secured to and projecting upwardly from said yoke.

2. A device of the class described, comprising a member, a block above and pivotally supported by said member and with limited complete freedom for motion lengthwise of the pivot relative to said member, a member pivoted on said block for rocking motion transverse to the pivot of said block, and a jack pin carried by said last mentioned member.

3. A device of the class described, comprising a member, a block above and pivotally supported by said member and with complete freedom for motion lengthwise of the pivot within limits relative to said member, means for adjusting said block angularly about its pivot, a yoke pivoted to said block for rocking motion transverse to the pivot of said block to said member, and a jack pin carried by said yoke and extending transverse to both pivots.

4. A device of the class described, comprising a supporting member, a block mounted for free linear motion on said supporting member and for rocking motion transverse to the direction of said linear motion, means for adjusting the angular position of said block about its rocking axis, an element pivotally supported on said block for rocking motion in a plane parallel to said linear motion, and a jack pin carried by said element.

5. In combination, a base, a post vertically adjustable on said base and having an extension at its upper end, a block pivoted laterally to the upper portion of said post, and extending over said extension, an adjustable abutment carried by said extension and supporting said block, an element pivoted to said block transverse to said block pivot, and a jack pin carried by said element.

6. In combination, a base, a post vertically adjustable on said base and having an extension at

its upper end, a block pivoted laterally to the upper portion of said post and with freedom for motion lengthwise of said pivot relative to said post and extending over said extension, an adjustable abutment carried by said extension and supporting said block, an element pivoted to said block transverse to said block pivot, and a jack pin carried by said element.

7. In combination, a base, a post vertically adjustable on said base and having an extension at its upper end, a block pivoted laterally to the upper portion of said post, and extending over said extension, an adjustable abutment carried by said extension and projecting through said base and supporting said block, an actuating element for said abutment beneath said base, an element pivoted to said block transverse to said block pivot, and a jack pin carried by said element.

KENNETH W. MACDONALD.
